UNITED STATES PATENT OFFICE

ALEXANDER STEPHEN KNOWLES, OF ST. LOUIS, MISSOURI; LOUISE H. KNOWLES, OF BAYSIDE, LONG ISLAND, NEW YORK, EXECUTRIX OF SAID ALEXANDER S. KNOWLES, DECEASED, ASSIGNOR TO TAR & PETROLEUM PROCESS COMPANY, OF CHICAGO, ILLINOIS, A CORPORATION OF ILLINOIS

OVEN OR RETORT FOR TREATING TARRY MATTER AND THE LIKE

Application filed May 26, 1926. Serial No. 111,678.

My invention relates to ovens or retorts and especially to ovens intended for dehydrating, distilling and cracking tars and oils or for coking the residue of petroleum distillation and cracking processes. On account of the high temperature required for such operations, it has heretofore been the practice to make such ovens of fire brick or other refractory material; and it is one of the objects of 5 my invention to devise an oven suitable for the purposes mentioned and which will operate in such manner as to enable steel plates or the like to be substituted in large part for the heavy and expensive refractory material 10 heretofore used. Another object is to facilitate and expedite the charging and discharging of the oven; to provide for the efficient transfer and conservation of heat and the driving off of the volatile matter during the 15 terminal stage of the process; and to provide for economy of fuel and the elimination of water or of other volatile matter. The invention consists principally in an oven with a floor heated from below and with a top portion of steel plate or the like. It also consists in such an oven provided with trackways extending endwise thereof and containers for loose carbonaceous material slidably mounted on said trackways. It also consists 20 in such an oven wherein the containers are supported slightly above the floor of the oven, and means for injecting steam or gas in the space between said floor and said containers. It also consists in certain details and 25 in the combinations and arrangements of parts hereinafter described and claimed.

In the accompanying drawings which form part of this specification and wherein like reference numerals refer to like parts 30 wherever they occur,

Fig. 1 is a vertical cross-section on the line 1—1 of Fig. 2 of a single chamber oven embodying my invention;

Fig. 2 is a vertical longitudinal section of 45 said oven on the line 2—2 of Fig. 1;

Fig. 3 is a vertical cross-section of a multiple chamber oven embodying my invention;

Fig. 4 is a horizontal sectional view of the oven shown in Fig. 3, the section being indicated by the broken line 4—4 of said Fig. 3; 50

Fig. 5 is a vertical longitudinal section of the oven shown in Fig. 3 on the plane indicated by the line 5—5 of Fig. 3; and

Fig. 6 is a longitudinal sectional view on the plane indicated by the broken line 6—6 55 of Fig. 3.

The oven illustrated in the accompanying drawings comprises a substantially rectangular retort chamber, underlying which is a base portion 1 of refractory material through 60 which three sets of flues extend horizontally. The uppermost set of flues 2 extend cross-wise of the length of the retort chamber or oven, from side to side thereof, and communicate at their ends with a lower set of flues 3, 3 which also extend inwardly or cross-wise through suitable checkerwork 4 from the opposite sides of the structure and communicate at their inner ends with longitudinally disposed flues 5, 5, the flues of the second set 70 on one side of the structure communicating with one of the longitudinal flues and the flues on the other side communicating with the other longitudinal flue. Both of the longitudinal flues communicate with a suitable stack 6 and each is provided with two dampers, one damper 7 controlling the passage to the stack and the other damper 8, which is located between said first mentioned damper 7 and the oven, controlling an opening to the atmosphere. Suitable pipes or jet 75 burners 9 extend through the opposite sides of the oven into the opposite ends of the flues of the first set and communicate through valved pipes 10 with a suitable fuel supply. The system of flues thus arranged constitutes 80 a regenerator and operates as follows: Assuming that fuel is being fed to the burners 9 on the right side of the oven, the valves in the supply pipes of the left side burners are 85

90

closed, the stack damper 7 of the longitudinal flue, with which the second set of flues on the right side communicate, is closed and the air damper 8 thereof opened, and the other stack 5 damper opened and the other air damper closed. Under these conditions, the fuel delivered by the right side burners is supplied with air that enters the right side longitudinal flue and passes through the checker- 10 work of the right side flues of the second set; and the products of combustion of the right side burners pass through the topmost flues and thence through the checkerwork of the left side flues of the second set and thence 15 through the left side longitudinal flue to the stack. In this operation, the products of combustion of the right side burners first heat the sole of the oven and then heat the left side checkerwork; and when the right 20 side burners are shut off and the left side burners used (the dampers being correspondingly changed) the air therefor is preheated by passing through the checkerwork on the left side which has already been heated by 25 the products of combustion of the right side burners. In practice, this alternation in the use of the right side and left side burners is effected at suitable intervals.

The floor of the retort chamber or oven is 30 preferably lined with sheets 11 of steel or other metal; and the top 12 of the oven is in the form of a flat or domeshaped steel roof which is supported on low walls 13 of refractory material and extends far enough 35 above the floor to afford room for the bed 14 of loose material hereinafter mentioned and an ample vapor space above the same. The low side walls are preferably provided with trackways 15 extending lengthwise thereof and adapted for carriers 16 to slide or roll upon. These carriers are of any suitable 40 form such as large steel containers or cars with lateral projections that overlap the side trackways and rest directly thereon or are provided with wheels or rollers that rest on 45 said trackway. The body of the carrier is preferably suspended between the sides of the oven but its sides are preferably spaced from the sides of the oven and its bottom is spaced 50 from the bottom of the oven. Preferably, the bottom of the carrier is a plate with perforations extending therethrough, whose margins 17 are flanged up so as to permit the passage of vapors upwardly through the perforations and still permit the accumulation 55 of a small depth of liquid in the carrier. The oven may be long enough to accommodate a number of such carriers, which may be positioned within and removed from the 60 oven through doors 23 at the ends thereof.

Inside the oven are a number of plates 18 that are hinged to the sides of the oven or adapted to be tilted on their edges along such sides, the inner margins of these plates 65 being normally held against or close to the

roof of the oven by suitable devices, such, for instance, as cables or chains 19 that pass down through the roof of the oven to the inner margins of the respective plates. The lines along which such plates pivot or swing 70 are preferably about the same elevation as the tops of the carriers so that, when the inner ends of such plates are let down, the plates will rest flatwise against the charge in said carriers and serve as lids therefor. Normally, the plates are held in their raised position, but they are lowered when spraying of the bed is finished and a higher temperature is required quickly to bring the contents of the container to dryness. 75

At one end, or preferably at both ends, the oven is provided with means 20 for feeding thereto the material to be treated. Such material comprises tarry and pitchy matter and the heavy viscous and solid residues of hydrocarbon cracking processes. The viscous liquid matter is heated suitably to make it fluid and is injected through a nozzle or spraying device 21 located preferably in the front or rear of the oven at a point above the top of the carriers; and such device is preferably arranged to permit it to be moved back and forth lengthwise of the oven and to be rotated on its axis. Preferably such manipulation is effected mechanically, continuously or at intervals, or by an attendant who regulates the feed according to the temperature, as shown by instruments, inside of the oven. 85

In practical operation, the carriers are filled to a greater or less depth with carbonaceous material 14, such as anthracite coal, or coke graduated as to fineness, and the flues are heated until the floor is raised to the required temperature, depending on the gravity of the material to be treated and the depth of the bed, (say, 500° to 1000° C.). The attendant then feeds the liquid carbonaceous material to be treated onto the surface of the beds in said carriers. As the beds are heated from below, the hottest part of the bed is the lowest part and the material fed to the bed reaches the coolest portion thereof first and travels towards the hottest portion. The result is that the most volatile content of the material undergoing treatment is vaporized at or close to the surface of the bed or even before reaching the bed, while the least volatile matter flows into the lower and hotter portion of the bed, where the liquid portion is vaporized and passes off through the outlet pipe 22. As the operation of vaporizing the material absorbs considerable heat, it may happen that the continuous feeding of an excessive amount of material will cool a portion of the bed below the point where the least volatile portion of the material is vaporized; and in this case, such unvaporized material is trapped at the bottom 100 of the bed and flows toward a portion of 105 110 115 120 125

- the carrier that has received a smaller amount of material and, therefore, remained hot enough to volatilize such liquid matter. If all or any portion of the oil or heavy, pitchy residue is to be removed from the oven, means such as pipes 24 are provided for drawing it off to be recovered on the outside as dehydrated or partially distilled product.
- 10 As stated above, the bottom of the carrier is spaced away from the bottom of the oven and has upwardly flanged openings therein. The purpose of this arrangement is to permit steam, to be forced into the space between the bottom of the carrier and the bottom of the oven, where it acts as a vehicle for conducting the heat from the bottom of the oven to the carrier and also to force its way through the openings in the bottom of the carrier and the bed of material therein to the upper portion of the oven. During this operation, it cooperates with the vapor of the material undergoing treatment in forcing the passageways therefor through said bed and also serves to entrain and carry such vapors to the space above the bed and thence also to the condensation chambers which communicate with the vapor space of the oven. Where the material undergoing treatment contains a considerable percentage of ingredients that volatilize at high temperatures, the use of steam in the manner stated is quite desirable; but where the material undergoing treatment does not require high temperature, such steam may be dispensed with.
- 15 The heating of the oven from below, as above described, has several important advantages. In the first place, the more volatile matter is eliminated in the surface portion of the bed without materially decreasing the temperature of the bottom of the bed which is, therefore, kept in condition to treat the material that is most difficult to volatilize.
- 20 In the next place, the greater portion of the work is done in the upper portion of the bed and the temperature in the vapor space of the oven is considerably lower even than the temperature of the surface of the bed. It is noted, however, that on account of the relatively low temperature in the vapor space, particularly in the absence of steam as mentioned above, the vapors must be eliminated by means of suction fans or other apparatus of the kinds usually used for the purpose.
- 25 Aside from these advantages, a sheet metal dome has the great advantage of being far less expensive than a dome of refractory material. Besides, it is practicable to make ovens with sheet metal domes any desired width; whereas, on account of its great weight and other physical difficulties, the practicable width of a dome of refractory material is necessarily limited. In the practice of my invention, it is desirable to make the oven wide enough to receive several carriers alongside of each other and to divide the space into a plurality of parallel retort chambers or sections by partition walls that separate one line of carriers from another. This arrangement is of great economic importance, because it reduces the amount of outer wall surface from which the heat would be wasted by radiation. A similar advantage attaches to the length of the ovens; for, as the furnaces are located on the sides, the retort chambers or ovens may be of any length required by economic or other considerations. Another important advantage of this arrangement is that the oven may be so fired that different temperatures may be obtained at different portions of the oven lengthwise. Each unit, composed of two or more retort chambers or sections, is a complete plant, flexible in its construction and operation, and in its heating system. The particular advantage in this type of regenerator in the complete unit is the amount of regeneration available by extending the checkerwork forming the regenerators as far as desired in the direction of the stack. The efficiency of the heating system in this way is increased to the economic limit.
- 30 The gas is burned on one side for a period of, say, thirty minutes, then reversed, the air to be preheated follows the gas flames and the waste products the opposite direction to the stack.
- 35 In the course of operation, the bed of material in a carrier becomes more or less coated or impregnated with a deposite of carbon; and when the deposit tends to fill the interstices in the bed to such extent as to interfere with the proper working thereof, the lid plates are raised, the door is opened, and the carrier is drawn out and discharged, then recharged, and restored to its former position. All of this can readily be done without interfering with the proper operation of adjoining sections of the oven.
- 40 Any material which contains binding property sufficient to make it hold together with strength to withstand mechanical means for discharging it may be charged onto the refractory floor of the oven to certain depths and heated to effect the binding together into a salable product. In this case, no containers are used, and no steel, or other metal floor is required.
- 45 My oven, especially my multiple retort chamber oven hereinbefore described, is suitable for use not only for the treatment of tarry matter but also for coking coal. When used as a coking oven, the carriers and their beds of material, and preferably also the metal floor lining, are removed and the coal charged onto the floor of the oven preferably through the hole provided therefor in the roof. When the operation of coking is completed, the coke is discharged in any usual

way, each chamber functioning as a complete unit.

What I claim is:

1. An oven of the kind described comprising a substantially oblong retort chamber having a charging door at one end, a floor of refractory material for said chamber, a plurality of parallel heating flues extending transversely under said floor from side to side of the oven, and longitudinal flues communicating with said transverse flues and with a stack.

2. An oven comprising a substantially oblong retort chamber having a floor of refractory material, heating flues extending transversely under said floor from side to side of the oven, laterally disposed burners communicating directly with the opposite ends of said heating flues, and longitudinal flues communicating with said transverse flues and with a stack.

3. An oven for treating tarry matter and the like comprising a retort chamber having a floor of refractory material, heating flues extending horizontally under said floor, a trackway in the retort chamber, loose material carriers movably mounted on said trackway, lids movably mounted in said chamber and adapted to be lowered onto the upper surface of the material in said carriers, a device for feeding such tarry matter above said material, the bottoms of said carriers being spaced above the bottom of the retort chamber, and a device for spraying steam into the space between the floor of said chamber and the bottoms of said carriers.

4. An oven for treating tarry matter and the like comprising a retort chamber having a floor of refractory material, heating flues extending horizontally under said floor, a trackway in the retort chamber, loose material carriers movably mounted on said trackway, lids mounted in said chamber to move into or out of position to cover said carriers, the bottoms of said carriers being spaced above the bottom of the retort chamber, a device for delivering such tarry matter above said material, a device for spraying steam into the space between the floor of said chamber and the bottoms of said carriers, and a device for delivering vapor from the upper portion of said retort chamber.

5. An oven for treating tarry matter and the like comprising a substantially oblong retort chamber having a floor of refractory material, a set of heating flues extending under said floor from side to side of said chamber, a second set of transverse flues below said first mentioned set, a third set of flues extending longitudinally of the oven and communicating with a stack and with the atmosphere, and provided with means for controlling their communication with the stack and with the atmosphere, said second set of flues communicating with the first set of flues near the

sides of the oven and communicating with the longitudinal flues near the middle of the oven, and burners at the opposite ends of the first mentioned flues, whereby the draft may be reversed and the air for the burners pre-heated.

6. An oven for treating tarry matter and the like comprising a plurality of horizontally elongated parallel retort chambers having a floor of refractory material, a set of heating flues extending under said floor from side to side of said oven, and transversely of the elongated chambers, a second set of transverse flues below said first mentioned set, a third set of flues extending longitudinally of the chambers and communicating with a stack and with the atmosphere, and provided with means for controlling their communication with the stack and with the atmosphere, said second set of flues communicating with the first set of flues near the sides of the oven and communicating with the longitudinal flues near the middle of the oven, and burners at the opposite ends of the first mentioned flues, whereby the draft may be reversed and the air for the burners preheated.

7. A multiple chamber distillation oven comprising a plurality of elongated parallel retort chambers having a floor, flues extending transversely of said oven under said plurality of chambers for heating said floor, and a roof for said oven, said oven having doors at one end of each chamber, a charging opening in the roof, and a vapor outlet for each chamber.

8. A distillation oven comprising an elongated retort chamber provided with a charging door at one end, heating flues extending transversely from side to side of said chamber under the floor thereof, heating means at the opposite ends of said flues, a stack at one end of the oven, separate flues extending longitudinally of the oven adjacent to the center line of said chamber, and communicating with the stack and with the atmosphere, dampers for controlling such communications, and flues connecting the opposite ends of said heating flues with said longitudinal flues respectively.

9. A distillation oven comprising an elongated retort chamber provided with a charging door at one end, a plurality of heating flues extending transversely from side to side of said chamber under the floor thereof at intervals along its length, heating means at the opposite ends of said flues, a stack, flues separately connecting the opposite ends of said heating flues with the stack, and means for reversing the flow of air through said flues.

10. A distillation oven comprising a horizontally elongated retort chamber divided by longitudinal partitions into a plurality of separate horizontally elongated compartments, charging doors at one end of

each of said compartments, a plurality of heating flues extending transversely from side to side of said chamber under said plurality of compartments at intervals along the length thereof, heating means at the opposite ends of said flues, a stack, flues separately connecting the opposite ends of said heating flues with the stack, and means for reversing the flow of air through said flues.

10 Signed at St. Louis, Missouri, this 21st day of May, 1926.
